UNITED STATES PATENT OFFICE.

DAVID BAUM, OF LIVERMORE FALLS, MAINE, ASSIGNOR TO THE BAUM MACHINE CO., OF LIVERMORE FALLS, MAINE, A CORPORATION OF MAINE.

MACHINE FOR TURNING SHOES AND THE LIKE.

Application filed April 5, 1924. Serial No. 704,437.

To all whom it may concern:

Be it known that I, DAVID BAUM, a citizen of the United States, and a resident of Livermore Falls, in the county of Androscoggin and State of Maine, have invented new and useful Improvements in a Machine for Turning Shoes and the like, of which the following is a specification.

My invention relates to a machine for automatically turning or reversing a shoe, or other articles which may be similarly treated, from wrong-side-out to right-side-out, or vice versa. In the manufacture of shoes of certain kinds the "uppers" are sewed to the soles with the "wrong" sides of both outwardly exposed. The parts, ultimately, are required to be reversed,—that is the already sewed shoe must be turned "right-side-out".

20 A method quite generally used to accomplish this result is first to turn down a portion of the upper at the heel end, reverse the counter, which latter operation partially turns the shank of the sole, continue the 25 turning from the ball of the sole, working toward the tip of the shoe, until the complete vamp has been turned inside out, with a consequent exposure of the reverse side of the sole. As an aid to the operator a 30 horn shaped arm is used against which to press the channel side of the sole to resist the pulling over force applied to the vamp. It is a very strenuous, slow operation, calling for great strength and endurance on the 35 part of the workman.

One object of my invention is to supply a device which will eliminate a greater part of this manual effort in the turning of a shoe. With the sole locked between two reciprocating plungers,—one above and one 40 below,—which act in synchronism and are in continuous contact with the sole during the entire turning period, the tendency to strain the upper is greatly reduced if not wholly eliminated and the loosening of the 45 seam is in a great measure prevented.

Another very important feature is the matter of time saved over the old hand method of turning. One stroke of the 50 plungers results in one shoe being turned whereas many movements were gone through before this was accomplished in the old way.

In my present invention I reverse the 55 sequence of turning movements by beginning on the tip end of the shoe, in contrast

with the hand method which starts with the shank.

In the construction of this machine I have incorporated features somewhat similar to ones found on a previous invention, 60 and on which I hold a United States patent, dated July 20, 1920, and numbered 1,348,077; and also on a co-pending application for a patent on improvements on certain elements in the machine covered by the 65 patent cited above,—this application being filed Aug. 20, 1923, and serial number of which is 660,000. The subject of this application concerned the support for the article being turned, and in my present one I 70 make no specific claims to this feature, although I have disclosed an improvement which may be advantageously adopted where heavy work, like shoes, are to be turned.

75 While I have illustrated and described my turner as a hand actuated machine it is obvious that a power driven one could easily be evolved. I also do not limit or confine myself to the exact details of construction but consider myself at liberty to adopt such changes as I deem proper, provided always that they come within the scope or intent of the appended claims.

80 In the drawings accompanying this specification,

Fig. 1 is a side elevation of the machine.

Fig. 2 is an end elevation of the same.

Fig. 3 is a fragmentary elevation, side view, and partly in section, which is taken 90 on line 3—3, Fig. 2.

Fig. 4 is a section taken on line 4—4, Fig. 3.

Fig. 5 is a part sectional view taken on 95 line 5—5, Fig. 3.

Fig. 6 is a section on line 6—6, Fig. 3.

Fig. 7 is a fragmentary end elevation, in part section taken on line 7—7, Fig. 3.

Fig. 8 is a fragmentary end elevation, in part section taken on line 8—8, Fig. 3.

Fig. 9 is a side elevation of the upper end 100 of the locating plunger.

Fig. 10 is a section of the same, taken on line 10—10, Fig. 9.

Fig. 11 is a perspective view of the oscillating roll on the locating plunger.

Figs. 11^a and 11^b are alternative designs 105 of the roll seen in Fig. 11.

Figs. 12, 13, 14 and 15 show consecutive 110 steps in the turning operation.

Fig. 16 is a side elevation, in part, of the machine, showing a shoe in position ready to be turned.

Fig. 17 is a sectional view through the 5 main bearings and actuating parts, taken on line 17—17, Fig. 18.

Fig. 18 is a side view, partly in section, of parts shown in Fig. 17, taken on line 18—18, Fig. 17.

10 Figs. 19 and 20 show end view and plan, respectively, of an alternative design of shoe support, and

15 Figs. 21 and 22 are sections taken on lines 21—21 and 22—22, respectively in Fig. 20.

Like characters of reference refer to similar parts throughout the different views of the drawings.

20 Mounted on a pedestal 1 and secured thereto by bolts 2, 2, is a column 3. Interposed between the pedestal and column and using the same securing bolts, is a knee 4. In bearings 5, 5 is journalled an oscillating shaft 6, upon which is loosely mounted a segmental gear 7. In the bearing 8 on the 25 column (3) and the bearing 9 on the knee (4) reciprocates a shaft or spindle 10. Cut on this spindle is a rack 11, adapted to engage the segmental gear 7. The lever 12 is the means through which the gear and spindle are actuated. Fixed to the spindle (10) is an arm 13 with means on the inner side for attaching a chain or cable to operate the counter-weight 14. On the outer end of this arm is an adjustably secured plunger 35 15 with the lower end slightly knurled, as at 15^a. On the forward side of the spindle (10) is adjustably secured a bar 16, with its lower end beveled, as at 16^a. The purpose of this bar will be hereinafter explained. On 40 the outer end of the knee 4 is formed a saddle 17 in which actuates the slide 18.

45 Referring to Fig. 3, the slide 18 carries on its inner end a roll 19 which is mounted in an adjustable block 20. Centrally of the slide is a projection 21 extending upwardly from the slide a spaced distance. Attached to the sides of this projection are resilient bars 22, 22, which extending upwardly and made into the proper form constitute the 50 support for the shoe being turned.

55 Directly beneath the projection 21, and in alignment therewith, is another projection 23. The two projections are bored to provide a bearing for the locating plunger 24. Toward the inner end of the slide is still another downwardly disposed projection 25, in which is rigidly secured the shaft 26. Mounted on this shaft (26) and sliding freely thereon is a latch carrier 27, and in an off-set portion 27^a is an adjustable bushing 28. This bushing is located in alignment with the bearing extending through projections 21 and 23 and is adapted to slidably receive the lower end of the locating plunger 24.

A threaded collar 29 adjusts the plunger 24 vertically. Interposed between the bushing 28 and the collar 29 is a helical spring 30 and on the extreme end of the plunger 24 is a nut 31.

70 Secured to the projection 23 is a stud 32 extending outwardly through the saddle and the spring tensioning bushing 33. A nut 34, outside of this bushing, acts as a stop to control and adjust the inward movement of the slide 18. A spring 35 pocketed in a bored portion of the saddle and thrusting against the bushing 33 and the projection 23 forces the slide toward the spindle 10, the nut 34 impinging on the bushing 33 with 75 the slide in its extreme inward position.

75 The latch carrier 27 has a rearward off-set portion 27^b, in which is an oblong hole 36. The spindle 10 extends downwardly through this hole and terminates in a reduced portion or a stud 37, the latter carrying a nut 38. Slidably mounted over this stud (37), and above the nut 38, is an angular connecting bar 39, pivotally connected to the foot 80 pedal 40, the latter being fulcrumed at 41 on the pedestal 1 and carries an adjusting stop screw 42 on its forward end.

85 By observing Fig. 7 it will be seen that the projection 25 carries a latch 43, secured to the rod 44, and extending downwardly 90 hooks on to the latch plate 45,—the latter secured to the carrier 27. Extending rearwardly, this rod (44) has a bearing at 46 on the knee 4. Mounted fixedly on and near the end of the rod 44 is an arm 47 carrying 100 a stop screw 48. A spring 49 normally holds the latch 43 in locked position.

95 Referring to Figs. 5 and 8, 50 is a latch having its upper portion 50^a bent at an angle and made into the form of a ring which encircles the spindle 10. This latch (50) is pivotally hung on the off-set portion 27^b of the latch carrier 27 and engages, at the proper time, the latch plate 51 sunk into a depression in the spindle 10. A screw 52 is 110 for the purpose of disengaging the latch (50) from the latch plate (51) on the upward movement of the carrier. A spring 53 keeps the latch normally against the spindle (10).

115 In Figs. 17 and 18 I have shown the parts having to do with the actuation of the turner. Outside of the right hand bearing 5 is a hand lever 12, preferably adjustably clamped to the shaft 6. Between the bearings and on the shaft 6, I loosely mount the segmental gear 7. Adjacent to the gear and securely fixed on the shaft (6) is a flanged hub 55 having an arcuate hole through the flange thereof to receive the pin 56 which is fixed in the gear 7. Secured adjustably to the hub 55 is a segment of a disc 56^a with the outer periphery having one edge beveled. In alignment with the face of this disc is a plunger 57, reciprocable in a bearing 58 130

formed on the inner side of the column 3.

On the lower side of the lever 12 I attach, over the rod 59, a counter-weight 60, the purpose of which will shortly be described.

As I stated in my preamble, I use on this shoe turner one element of a machine already patented by me. This element is the supporting member 61, shown in section in Figs. 12, 13, 14 and 15, and in full in Figs. 10 and 2. Briefly, it consists of resilient arms extending upwardly from rigidly secured lower extremities, and terminates at the top in reversed U shaped clamps, one disposed within the other with their open sides facing and forming together an expansible tubular structure through which the shoe is forced downwardly as it is turned. I have somewhat improved this element in one particular,—namely the matter of decreasing the friction of the sole as it is bent over the top of the support while being forced down into the latter. An embodiment of this idea is illustrated in Figs. 19 and 20, in which is shown small rolls 62, 62 rotatable over pins 25 63, 63,—a roll being mounted on each of the members of the support.

The construction of the upper end of the locating plunger 24 is seen in Figs. 9 and 10. The plunger is bifurcated at the extreme upper end and within the bifurcations 24^a, 24^b is a roll 64, preferably but not necessarily covered by some slightly resilient substance, such as rubber or fabric, to eliminate the possibility of marring the outer surface of the sole and also to prevent the slipping of the sole on the roll were it too smooth and frictionless. A recess 65 is cut in the side of the roll and a flat spring 66, which is secured in a slot 67 in a plug 68 inserted in a hole in the plunger, enters and holds the roll normally against a stop screw 69 operating in an arcuate cut-away portion 70 on the end of the roll. In locating a shoe over this roll the action of the upper plunger, when it is being aligned with the shoe support, tends to turn this roll until the opposite end of the slot 70 impinges on the screw 69. This rolling action greatly facilitates the initial turn over of the tip of the sole.

In Figs. 11^a and 11^b I illustrate alternate designs for this roll. In the former the side is cut down leaving a shoulder 71 against which the tip of the sole may seat. In the latter I flatten that portion, 72, which the rolling action, incident to the locating operation, will eventually bring to the top central line,—or directly in line with the upper plunger,—and the sole, seated on this flattened surface will assist in keeping the roll steady and free from wobbling as it proceeds downward through the support.

In describing the operation of this machine it will first be well to state that the latch carrier 27 is placed in a position as seen in Figs. 1, 2 and 3,—the latch 43 hold-

ing the carrier, temporarily in this locked position. The latch 50 is not as yet functioning,—merely lying against the side of the spindle 10. The position of the hand lever 12 is as shown in full lines in Fig. 1.

Now the first move is to place an unturned shoe over the locating plunger 24 (see Fig. 12). The foot pedal is next brought into action and is forced downwardly until it comes within a spaced distance of abutting on the base of the machine. The upper plunger is now in a position as seen in Fig. 13,—the two plungers being out of alignment, the beveled portion 16^a of the bar 16 just contacting with the roll 19 and the latch 50 not yet locked on the spindle 10. The remainder of the foot pedal movement brings the upper plunger downwardly and at the same time the block 16 forces the slide outwardly bringing the two plungers into alignment and forcing the locating plunger 24 a spaced distance into the shoe support 61,—as seen in Fig. 14. By utilizing the foot in starting the actuating parts, the hands of the operator are left free to place and adjust the shoe over the locating plunger, between which and the upper or reciprocating plunger the sole of the shoe will be strongly gripped before it becomes necessary to disengage the hands to operate the hand lever.

At this time the latch 50 has locked into the spindle 10, the spring 30 put under a slight compression, which may be varied to suit the particular work in hand, the hand lever 12 carried down into position 12^a (see Fig. 1) and the segmental disc 56^a moved into close contact with the plunger 57; but the latch carrier is still in locked position,—preventing, temporarily, further movement downwardly of the plungers.

By reference to Fig. 18 it will be seen that the lever 12 is in fixed relationship to the flanged hub 55, from the fact that they are both secured to the shaft 6, and also it will be observed that the pin 56, fixed in the gear 7, occupies a position in the forward end of the arcuate slot 55^a, which locates the lever in a position indicated by 12^a, Fig. 1 and Fig. 18, after the full stroke of the foot pedal is made. And in connection with the foregoing I will state that the object of and reason for placing the counter-weight on the hand lever is to normally hold the forward end of this slot against the pin 56, the slot (55^a) providing the means for a slight movement of the hand lever and the segmental disc 56^a,—the latter unlocking the latch 43,—without movement of the gear 7 and the spindle 10.

Accordingly, the next move is to manipulate the hand lever, and a few degrees of movement forwardly, or to position indicated by 12^{aa}, will carry the disc 56^a over the plunger 57 forcing it down against the

arm 47 and tripping the latch 43. By this time the upper or opposite end of the arcuate slot 55^a will have contacted with the pin 56 which will again start movement of the 5 gear 7, the spindle 10, the latch carrier 27 and of course the two plungers 15 and 24, between which the sole of the shoe is held by the strong, yielding grip of the plungers and is carried downward through the shoe 10 support 61 until the shoe has been completely turned. After the proper length of stroke to properly turn the shoe is determined the stop collar 73 may be adjusted on the spindle 10, so that further action downwardly of 15 the plungers will not be made.

After the completion of the foot pedal stroke and the hand lever is being operated, the stud 37 telescopes the connecting bar 39. The hand lever is used for the entire return 20 stroke and the plungers retain their grip on the sole during the entire turning and expelling operations. When the lever arrives back at the 12^a position the tripping and locking of the latches takes place as when 25 on the downward stroke,—only in the reverse order.

One point I wish to emphasize, in concluding, concerns the functioning of the plunger 15 in turning the tip of the sole over the 30 end of the plunger 24. The contacting points are wholly on the sole and not the upper and it remains thus throughout the whole turning operation.

Having thus described my invention, 35 what I claim is:

1. In a machine for turning shoes and the like, the combination, with shoe supporting means and a reciprocable plunger normally out of alignment with said supporting 40 means and in operation adapted to act on one side of the sole of a shoe, of a second plunger reciprocably mounted within said shoe supporting means and adapted to act on the opposite side of said sole of said shoe 45 mounted thereon, said second plunger being capable of recession within said shoe support by the thrusting action of said reciprocable plunger first mentioned,—the two plungers co-acting to grip said sole while 50 being forced into said supporting means, means for aligning the two said plungers, means for causing a rolling action to take place on the interposed sole by simultaneously moving one plunger perpendicularly 55 and the other horizontally and means for actuating said first mentioned reciprocable plunger.

2. In a machine of the class described, a 60 support for a shoe or other article to be turned, said support at its supporting end being expansible and of a form to permit entrance of a shoe being turned and to extend about the turned shoe, a retractile plunger operating within said expansible 65 shoe support, and adapted to recede with

the turning of the shoe, a reciprocable plunger, means to position said reciprocable plunger disaligned with the first plunger and in position to engage the shoe at a side of the first plunger, means to shift said second 70 mentioned plunger to a position in alignment with the first plunger, and means for actuating said second plunger in its said aligned position.

3. In a machine for turning shoes and the like, the combination, with a shoe turning support consisting of two flexible members fixed at their base and having their opposite ends bent into U shapes, with the flattened sides of one yieldingly disposed with- 75 in the other and jointly having a tubular formation and a reciprocable plunger adapted to enter and move a spaced distance within said support, of a second plunger, yieldingly co-acting with said reciprocable plunger, and operating within said shoe turning support and normally projecting a spaced distance from out of the latter, means for obtaining a preliminary bend to the tip of the sole of the shoe to be turned, into a sub- 80 stantially right-angular form preparatory to a complete turning of the shoe, said means consisting of parts necessary to obtain a combination of two right-angularly disposed movements of the two plungers,—one 85 acting horizontally and the other vertically, means for varying the resistance of said second mentioned plunger to the thrusting action of said reciprocable plunger, the sole 90 of a shoe interposing, and means for actuating the said reciprocable plunger.

4. In a machine for turning shoes and the like, the combination, with expansible tubular shoe supporting means, of a reciprocable plunger normally in dis-alignment with 105 said supporting means, a retractile shoe locating plunger adapted to operate reciprocably within said supporting means, an oscillative roll mounted on the top of said locating plunger, means to restrict the oscillations of said roll, means for bringing said reciprocable plunger into accurate alignment with said locating plunger at a pre-determined point in the stroke of the former 110 and means for actuating said reciprocable plunger.

5. In a machine for turning shoes and the like, the combination, with shoe supporting means, of a reciprocable plunger located 115 above and out of alignment with said supporting means, means for actuating said reciprocable plunger, means, co-acting with said last mentioned means, for bringing said supporting means into near alignment with 120 said reciprocable plunger, a locating plunger adapted to operate reciprocably within said supporting means, resilient means to resist the recession of said locating plunger into said supporting means and means 125 whereby a predetermined resistance between 130

the reciprocable plunger and the locating plunger, while the sole of a shoe interposes, may be maintained during the entire turning operation.

5 6. In a machine for turning shoes and the like, the combination, with shoe supporting means and a reciprocable plunger adapted to enter said shoe supporting means, of a second plunger, co-acting at predetermined times, with said reciprocable plunger, and located within and extending a spaced distance above the said shoe supporting means, a latch carrier, means on said latch carrier for guiding and restricting the movement 10 therethrough of said second mentioned plunger, means on said carrier whereby said second mentioned plunger may yieldingly resist the thrust of said reciprocable plunger, means for locking said carrier at predetermined times against the thrust of said reciprocable plunger and means for actuating the latter.

7. In a machine for turning shoes and the like, the combination, with a reciprocable plunger and shoe supporting means, of a locating plunger adapted to operate within and above said supporting means and parallel to the line of action of said reciprocable plunger, means for bringing said shoe supporting means out of alignment with said reciprocable plunger, means for bringing said shoe supporting means into alignment with said reciprocable plunger, a latch carrier, means for locking said latch carrier against vertical movement on the said machine, means on said carrier whereby a yielding resistance to the movement of said locating plunger against the thrust of the said reciprocable plunger may be had, means 30 whereby said yielding resistance may be adjusted to varying degrees of potency,—either increasing or decreasing, means for unlocking said latch carrier, a reciprocable shaft in fixed relation to said reciprocable 35 plunger and means for actuating the said shaft.

8. In a machine of the class described, the combination, with shoe supporting means and a reciprocable plunger adapted to move into and out of said supporting means, of a slide, reciprocably mounted on a fixed portion of the said machine, said slide carrying the said shoe supporting means, a bearing on said slide, a second plunger adapted to reciprocate in said bearing and to extend into and above said shoe supporting means, means for moving the said shoe supporting means out of alignment with the said reciprocable plunger, a latch carrier, a latch mounted on said slide and adapted to hold said latch carrier in fixed

relationship to the said slide at predetermined times, means on the said latch carrier for giving the said second mentioned plunger a yielding resistance against the 65 thrust of said reciprocable plunger, the two plungers acting, respectively, on opposite sides of an interposing sole, a shaft, means on said shaft for supporting the said reciprocable plunger, means on said shaft for 70 bringing said shoe supporting means into alignment with said reciprocable plunger, a second latch, mounted on said latch carrier and adapted to act on the said shaft at predetermined times whereby the said latch 75 carrier may be secured to the said shaft and reciprocate therewith, means for unlocking said second latch from said shaft, means for unlocking said latch carrier from 80 said slide and means for actuating the said shaft.

9. In a machine for turning shoes, an expandible shoe turning support adapted to be inserted in the shoe to be turned and adapted to permit of the shoe being forced into said support for the said support to embrace the shoe, a retractile plunger adapted to pass through said support to engage the shoe to be turned, a reciprocable plunger normally out of alignment with said support and said first mentioned plunger, means to give lateral movement to the second mentioned plunger while engaged with the shoe for displacing the latter to aline the two plungers and dispose a portion of the shoe sole therebetween, and means to reciprocate the second mentioned plunger when alined to cause recession of the first plunger and turning of the 95 shoe into said support. 100

10. In a machine for turning shoes, a plunger adapted to enter the shoe to be turned and to recede with the turning of the shoe, a second plunger, means to position the second plunger disaligned with the first plunger and engaging the shoe to be turned, and means to cause an alining of the plungers and a shifting of the shoe to dispose a portion of the sole between the plungers; together with means to reciprocate the second plunger for turning the shoe. 105

11. In a machine for turning shoes, a plunger adapted to enter the shoe to be turned and to recede with the turning of the shoe, a second plunger, means to position the second plunger disaligned with the first plunger and engaging the shoe to be turned, and means to cause an alining of the plungers and a shifting of the shoe to dispose a portion of the sole between the 115 120 plungers.

DAVID BAUM.
